UNITED STATES PATENT OFFICE

138,204

DESIGN FOR A BELT RACK

Manfred Rosenblatt, Kew Gardens, N. Y.

Application May 6, 1944, Serial No. 113,496

Term of patent 3½ years

(Cl. D80—9)

To all whom it may concern:

Be it known that I, Manfred Rosenblatt, a subject of the Principality of Liechtenstein, residing at Kew Gardens, in the county of Queens, and State of New York, have invented a new, original, and ornamental Design for Belt Racks, of which the following is a specification, reference being had to the accompanying drawing, forming part thereof.

Fig. 1 is a top plan view of a belt rack, showing my new design.

Fig. 2 is a side elevational view; and
Fig. 3 is a top plan view thereof.

I claim:

The ornamental design for a belt rack, substantially as shown.

MANFRED ROSENBLATT.
